UNITED STATES PATENT OFFICE.

LEWIS FERRY MOODY, OF PHILADELPHIA, PENNSYLVANIA.

HYDRAULIC DRAFT TUBE.

Original application filed November 28, 1922, Serial No. 603,769. Divided and this application filed March 26, 1926, Serial No. 97,584. Renewed May 14, 1928.

This invention relates to hydraulic turbines and in particular to an improved means for receiving water from the turbine runner and delivering it to the tail race. More particularly my invention relates to means of this character wherein the water is turned or spread out from a direction along the axis of the runner into diverging radial directions and is subsequently turned into a single direction for discharge into the tail race. This application is a division of my copending application, Serial No. 603,769, filed November 28, 1922.

In many modern hydraulic power plants the turbines are placed in a row with vertical shafts, the water entering the turbines on one side of the row from the penstocks or forebay and discharging at the other side into the tail race. The water leaves the runners in a downward direction at high velocity and some means should be provided which will reduce this velocity so as to correspondingly reduce the back pressure on the turbine runners and which will likewise turn the flow into a horizontal downstream direction. This means should be constructed so as to perform these functions without appreciable losses of energy and should itself occupy a minimum space. The last condition is particularly desirable in order that the turbines themselves may be closely spaced and the power house dimensions made as small as possible.

For the purpose of reducing the velocity, draft tubes have been used which direct the flow from the runner radially outward on spreading lines and discharge it horizontally in every direction. The flow may then be received by a collector which turns it into a common downstream direction. Certain portions of the flow must be turned through substantially 180° while other portions, which leave the tube in a direction more nearly approaching the downstream do not have to be turned through so great an angle.

If an unlimited space were available the initial velocity with which the water enters the draft tube could be reduced and its kinetic energy turned into effective head for the turbine by the use of the spreading action alone, that is, the water could be discharged outwardly in all directions at such a low velocity that but little kinetic energy would remain in it. The problem of collecting the flow and discharging it downstream would be solved by the use of any suitable collector

which would not cause an appreciable loss of head.

With the available space limited, however, it is desirable to provide a draft tube of such dimensions that the water discharged into the collector will retain a portion of its kinetic energy and that the collector be so designed as to reduce further the velocity of the water and to regain this energy. The water leaving the draft tube in an upstream direction may be conveniently collected from the tube by one or more spiral passages extending circumferentially around the cylindrical outlet of the tube and discharging tangentially downstream toward the tail race. These spiral passages should be enlarged at a rate greater than is necessary to accommodate the cumulative flow so that the velocity of the flow therethrough will be gradually reduced.

One of the objects of the present invention is to provide an improved collector of this character which is designed to receive a flow of considerable velocity from the draft tube and is adapted gradually and uniformly to reduce the velocity of this flow and so regain its kinetic energy.

Another object of my invention is to provide in addition to the spiral collector passages above described an effective means for decelerating that portion of the flow which does not enter the spiral passages.

Numerous other objects and advantages will appear from the following description taken in connection with the accompanying drawings which illustrate certain of the preferred embodiments of my invention and wherein

Fig. 1 is a sectional view on line 1—1 of Fig. 2,

Fig. 2 is a horizontal sectional view on the line 2—2 of Fig. 1,

Fig. 3 shows a vertical sectional view on the line 3—3 of Fig. 2,

Fig. 4 shows a vertical section taken on the line 4—4 of Fig. 2 looking in the direction of the arrows,

Fig. 5 shows in vertical section on the line 5—5 of Fig. 6, a modification,

Fig. 6 is a horizontal section on the line 6—6 of Fig. 5,

Fig. 7 is a vertical section on the line 7—7 of Fig. 6, and

Fig. 8 is a vertical section on the line 8—8 of Fig. 6 taken in the direction of the arrows.

Referring to the figures, reference char-

acter 20 indicates generally the primary draft tube and 21 the collector. The primary draft tube as shown is formed of an outer wall 22 having a slightly tapered or conical 5 upper portion 23 and gradually curved outward to a horizontal direction at its lower end, the lower end of the draft tube having a barrel portion 28 depending into the collector. The outer surface of the main body 10 portion of the barrel is cylindrical. Projecting upwardly from the floor 25 of the collector passage into the flaring end of the wall 22 and concentric therewith is a cone 26 whose concave surface is formed in relation to the 15 outline of the flared end of the wall 22. The outer wall 22 and cone 26 together form the primary draft tube which serves to direct the flow downward from the turbine runner and outwardly into a horizontal plane. The cross 20 sectional area of this tube as shown increases gradually so as to give a gradual deceleration to the meridional components of the flow, and at the same time the tube is adapted to handle efficiently flow containing whirling 25 components about the turbine axis.

In the form shown in Figs. 1 to 4 I provide a single curved collector channel which starts at a lateral point 40 at the mouth of the draft tube, is curved around the axis of the tube 30 through an angle of approximately 180° and terminates in a straight passage 47 having a direction downstream and substantially tangential to the draft tube. The inner and outer walls of this passage are vertical and its 35 upper and lower walls horizontal except that the upper wall 50 of the outer passage is inclined upward at an angle preferably not to exceed about 15°.

The passage 49 for discharging the direct 40 flow is substantially rectangular in cross-section and is formed by the floor 25, top wall 50' which is inclined upwardly at an angle not to exceed about 20°, side wall 51 and wall 52, the last being formed by a partition 53 45 which separates the passage for the direct flow from the end of the curved passage. The top wall 50' thereby forms an extended roof with which the primary draft tube merges to form the direct discharge passage which is 50 also substantially tangent to the primary tube or passage at a point lateral of or offset from the axis of the primary tube. It is also seen that only the two passages 47 and 49 are provided, these having upper walls or roofs at 55 different elevations.

The form of my invention shown in Figs. 5 to 8 is similar to that shown in Figs. 1 to 4 except in the former the curved collector passage does not terminate in a straight section but continues to curve so that the total curve exceeds 180° and also continues to flare horizontally through its entire course. This passage is quite narrow but considerably higher than those shown in previous figures. 60 The partition of Figs. 1 and 2 is omitted,

there being merely a strut 56 between the upwardly extending top wall of the passage for the direct flow and the floor 25. The cone shown in this form of my invention extends upwardly through the entire draft tube to the 70 runner and the runner shown is of the propeller type. If desired the form shown in these figures may have an over-hanging passage collector.

While I have shown a primary draft tube 75 which is constructed to progressively increase in area, in certain cases it may be necessary to employ one whose principal function is to turn the water outwardly in all directions without being able to produce any substantial decrease in velocity. With the use of such tubes it would be necessary to employ a collector which will reduce the velocity of the flow from an amount which is only slightly less than its velocity at the runner. 80

Moreover even with these turbines wherein the discharge velocity from the spreading conduit is sufficiently small to be so thrown away when the turbine is operating at its 85 normal capacity, it must be considered that under the usual conditions turbines are frequently called upon to operate at capacities considerably above normal and when so operating the discharge velocity from the spreading conduit rapidly increases and may represent a very material amount of velocity head in comparison with the available head on the plant. A failure to provide for efficient deceleration of this velocity of discharge from the spreading or primary draft tube may therefore materially restrict the 90 full-load capacity of the turbine even in cases where the primary or spreading conduit is sufficient in itself to take care of the ordinary and normal load conditions with 95 high efficiency. The proper formation of the collector passages therefore may have a vital effect upon the full power capacity of the turbine. 100

It should also be considered that by providing efficient collector passages the size of the primary portion of the draft tube may be cut down without serious loss of draft tube efficiency, but with a material reduction in the over-all dimensions of the entire draft tube, and consequently of the power-house and sub-structure. 110

While I have shown my invention as applied to turbines having vertical axes it is 115 obvious that with slight modification of structure my invention is likewise applicable to turbines having horizontal shafts. I have also shown a draft tube and collector which receive water in an axial direction and discharge it in a radial or tangential direction, that is, along a plane at substantially right angles to the axis of the draft tube. It is 120 of course apparent that the angle between the axis and the discharge direction need not be exactly a right angle as conditions of practice 125 130

might make it desirable to increase or decrease this angle somewhat.

While in the foregoing description I have distinguished between the primary draft tube and the collector, it will be recognized that in other forms of my invention the primary draft tube and collector function may be so merged that no one portion of the structure may be termed a primary draft tube and the remainder a collector. Such cases may nevertheless fall clearly within the scope of the present invention as set forth in the appended claims.

By radially spreading draft tube as employed in the claims I mean a tube which discharges the flow radially outward in all or substantially all directions, it being understood of course that such flow while passing outward may also have tangential and in certain cases axial components of velocity.

I claim:

1. A turbine having a draft tube formed of an outer circular spreading wall and a central cone projecting into the space surrounded by said wall, said spreading wall at the outlet of said tube being cut away to form a spiral collector passage, and said spreading wall being continued in one direction to form an inclined wall of a second passage which receives the downstream flow directly from said tube, and a partition for separating said spiral and downstream passages.

2. A turbine having a draft tube formed of an outer circular spreading wall and a central cone projecting into the space surrounded by said wall, said spreading wall at the outlet of said tube being cut away to form a spiral collector passage, and said spreading wall being continued in one direction to form one wall of a second passage which receives the downstream flow directly from said tube, and a partition disposed between said spiral and downstream passages, one of said passages being located tangential to said tube and adapted to receive therefrom a flow having a tangential component of velocity.

3. A turbine having a draft tube formed of an outer circular spreading wall and a central cone projecting into the space surrounded by said wall, said spreading wall at the outlet of said tube being cut away to form a spiral collector passage of rectangular cross section, and said spreading wall being continued in one direction to form one wall of a second passage which receives the downstream flow directly from the tube, and means forming a wall for both of said passages.

4. A turbine having a draft tube formed of an outer circular spreading wall and a central cone extending through the entire space surrounded by said wall, said spreading wall at the outlet of said tube being cut away to form a spiral collector passage of a gradually increasing cross section and said wall in one direction being continued along a surface

which is slightly inclined from the normal to the axis of said tube to form one wall of a second passage which receives the downstream flow directly from said tube, and means forming another wall of one of said passages.

5. In a turbine a radially spreading draft tube and a collector adapted to receive the flow from said tube and being offset with respect to said tube, said collector being of progressively increasing area, and adapted to produce a gradual deceleration of flow therethrough and being provided with a partition to prevent the mingling therein of streams of different velocities.

6. A turbine formed with a draft tube and a collecting chamber, the outlet of said draft tube being partly formed by a projection extending from the wall of said collection chamber, said projection being extended in a downstream direction and offset relative to said tube, and a pier between the extension and opposite wall for supporting said projection.

7. A draft tube formed by two concentric surfaces of revolution turning from a substantially axial direction to a radially outward direction, said surfaces terminating at a greater distance from the axis in one portion of the circumference than the remaining portion and a collector surrounding said tube and extending in a downstream direction therefrom, said collector having a portion of its floor and roof diverging in the direction of flow and the outer one of said concentric surfaces terminating within said collector passage at a point below the adjacent roof portion of the collector passage.

8. The combination with a draft tube, of a collector having a passage provided with a spiral wall starting at a lateral point of the draft tube, and means forming a second passage for receiving the direct downstream flow from the draft tube.

9. The combination with a draft tube, of a collector having a passage provided with a spiral wall starting at a lateral point of the draft tube, and means forming a second passage for receiving the direct downstream flow from the draft tube, said direct downstream passage extending inwardly from said lateral point to a point intermediate said lateral point and the spiral wall.

10. The combination with a draft tube, of a collector having a passage provided with a spiral wall extending in an upstream direction from a lateral point of the draft tube and curving into a downstream direction, and means forming a passage for directly discharging the downstream flow from the draft tube, the depth of said spiral wall being greater than that of the direct discharge passage.

11. The combination with a draft tube, of a collector having a passage provided with a spiral wall extending in an upstream direc-

- tion from a lateral point of the draft tube and curving into a downstream direction, and means forming a passage for directly discharging the downstream flow from the draft tube, the depth of said spiral wall being greater than that of the direct discharge passage, and said direct discharge passage having a vertically inclined surface in the downstream direction.
10. 12. The combination with a draft tube, of a collector having a passage provided with a spiral wall extending in an upstream direction from a point laterally of the draft tube and then curving into a downstream direction, thereby permitting upstream flow from the draft tube to be turned in a downstream direction, means forming a passage extending in a downstream direction for receiving the direct downstream discharge from the draft tube, and a cone disposed in said draft tube for directing fluid flow to the direct discharge passage and to said passage having said spiral wall.
15. 13. The combination with a draft tube having a flaring inner wall and a projecting barrel portion, a collector passage surrounding said barrel, an outer portion of the main body of said barrel being cylindrical, and another portion of the draft tube merging with an extended roof of said collector passage in a downstream direction.
20. 14. The combination with a draft tube having a flaring inner wall and a projecting barrel portion, a collector passage surrounding said barrel, an outer portion of the main body of said barrel being cylindrical, and another portion of the draft tube merging with an extended roof of said collector passage in a downstream direction, said passage which surrounds said barrel having a spiral wall.
25. 15. The combination with a draft tube, of a collector passage for receiving the discharge from said tube, comprising means forming a passage substantially tangent to said draft tube and being offset with respect to the central downstream axis of the collector passage, and means forming a second passage surrounding one side of the draft tube, one of said passages having a roof disposed at an elevation different from the roof of the other passage.
30. 16. The combination with a draft tube, of a collector passage for receiving the discharge from said tube, comprising means forming a passage substantially tangent to said draft tube at a lateral point thereof, means forming a second passage surrounding one side of the draft tube, one of said passages having a roof disposed at an elevation different from the roof of the other passage, and a pier disposed at the juncture of said roofs for supporting the same from the floor of said passages.
35. 17. The combination with a draft tube, of a collector passage constituting only two downstream passages, one of which has a roof disposed at an elevation different from the roof of the other passage.
40. 18. The combination with a draft tube, of a collector passage having only a pair of downstream passages whose combined width is offset with respect to the draft tube axis, and the roofs of the respective passages being at different elevations.
45. 19. A turbine having a draft tube formed of an outer circular spreading wall and a central cone projecting into the space surrounded by said wall, said spreading wall at the outlet of said tube being cut away to form a spiral collector passage, and said spreading wall being continued in one direction to form an inclined horizontally extending wall of a second passage which receives the downstream flow directly from said tube, and a partition spaced downstream from said cone for separating said spiral and downstream passages.
50. 20. In a turbine a radially spreading draft tube and a collector adapted to receive the flow from said tube and being offset with respect to said tube, said collector being of progressively increasing area, and adapted to produce a gradual deceleration of flow therethrough and being provided with a partition to prevent the mingling therein of streams of different velocities.

LEWIS FERRY MOODY.
